UNITED STATES PATENT OFFICE.

GEORGE BRAIN, OF TIFFIN, OHIO, ASSIGNOR TO STANDARD SANITARY MANUFACTURING COMPANY, OF PITTSBURGH, PENNSYLVANIA, A CORPORATION OF NEW JERSEY.

DESIGN FOR A LAVATORY.

Application filed February 24, 1928. Serial No. 25,558. Term of patent 14 years.

To all whom it may concern:

Be it known that I, GEORGE BRAIN, a citizen of the United States, and residing at Tiffin, in the county of Seneca and State of Ohio, have invented a new, original, and ornamental Design for a Lavatory, of which the following is a specification, reference being had to the accompanying drawing, forming a part thereof, which shows a perspective view of the article showing my new design.

I claim:

The ornamental design for a lavatory, substantially as shown.

GEORGE BRAIN.
